GATE VALVE

William E. Lowrey and Clifford E. Anderson, Houston, Tex., assignors to ACF Industries, Incorporated, New York, N.Y., a corporation of New Jersey

Filed Dec. 22, 1964, Ser. No. 83,125

Term of patent 14 years

(Cl. D91—3)

FIGURE 1 is an elevational view of a gate valve, showing our new design.

FIGURE 2 is a plan view of the gate valve of FIGURE 1.

FIGURE 3 is a bottom view of the gate valve of FIGURE 1.

FIGURE 4 is a right side elevational view of the gate valve of FIGURE 1.

The opposite end and side views of the valve are substantial duplicates of the end and side views illustrated in FIGURES 1 and 4, respectively.

The dominant features of the design illustrated in the various figures reside only in the features shown in full lines.

We claim:

The ornamental design for a gate valve, as shown and described.
